HYDRAULIC SYSTEM

Arthur H. Swenson and Phillip A. Anderson,
Rockford, Ill., assignors to Sundstrand Machine
Tool Co., Rockford, Ill., a corporation of Illi-
nois

Application July 8, 1942, Serial No. 450,134

18 Claims. (Cl. 60—53)

The invention relates generally to hydraulic systems and more particularly to hydraulic systems particularly adapted for driving a carriage or other member of a machine tool.

One object of the invention is to provide a hydraulic system including a transmission operable over a range of feed rates and having dog or automatically operated control means for causing the transmission to operate at a predetermined feed rate and means permitting manual control obtaining operation of the transmission at any desired feed rate within said range.

Another object is to provide such a hydraulic system wherein the previously used feed rate is available again for automatic control after the use of manual control for the same or other feed rates.

Another object is to provide in such a hydraulic system an optionally operable manual control means having a handle shiftable from a neutral position to different forward and reverse feed positions on opposite sides of the neutral position, the feed rates being somewhat proportional to the distance the handle is moved from neutral position.

Another object is to provide a hydraulic system including a transmission operable in forward or reverse over a range of feed rates, hydraulically operated means causing operation of the transmission in either direction at a predetermined feed rate, and means relieving the hydraulic pressure in the hydraulically operated means to permit direct manual adjustment thereof in either direction and to an extent obtaining any feed rate within the feed range.

Another object is to provide in a hydraulic system operable over a range of feed rates and having control means including a fluid pressure actuated stop determining the preadjusted feed rate, means for relieving the fluid pressure on the stop to permit direct manual adjustment of the control means throughout the entire range of feed rates.

Another object is to provide in a hydraulic system, including a transmission having a main pump and a motor operating in a closed circuit and a pump for supplying makeup fluid, a valve means operable to interconnect the inlet and outlet ports of the main pump and to connect the same to tank through a restricted orifice.

A further object is to provide in a hydraulic system, having hydraulically actuated control means and means for relieving a part of the control means of hydraulic pressure to permit direct manual operation, valve means associated with a remaining part of the control means permitting

discharge of fluid under pressure generated by manual operation of the control means.

Other objects and advantages will become apparent from the following description taken in connection with the accompanying drawings, in which:

Fig. 1 is a diagrammatic view of the hydraulic system with the transmission shown partially diagrammatically and partially in actual construction, and with certain valves enlarged better to disclose annular recesses and grooves thereof. The system is shown in its neutral stage.

Fig. 2 is a diagrammatic view of the hydraulic system similar to Fig. 1 but showing the system in hydraulic control stage.

Fig. 3 is an enlarged view of the main valve in one of its rapid traverse positions.

Fig. 4 is an enlarged view of the changeover valve in its energized position.

Fig. 5 is an enlarged view of the shunting valve in its deenergized position.

Fig. 6 is an enlarged view of the pressure reducing valve in a position which it assumes temporarily during direct manual control of the hydraulic system.

Fig. 7 is a front elevational view of a machine tool carriage or table, partly in section and diagrammatic.

While there is illustrated in the drawings and will hereinafter be described in detail a preferred embodiment of the invention, it is to be understood that the invention is not limited to the particular embodiment and arrangement shown. On the contrary, it is contemplated that various changes may be made by those skilled in the art without departing from the spirit and scope of the invention as defined in the appended claims.

The system includes a fluid transmission comprising a casing 20 having a detachable end member 21. The lower portion of the casing is occupied by a pump P and the upper portion by a motor M. A single cylinder block 24 is secured in the casing and has an annular series of pump cylinders 26 and an annular series of motor cylinders 27 formed therein. Pistons 28 in the pump cylinders are arranged to be actuated by means of a wobbler device 29 which is pivotally mounted on a drive shaft 30 by means of a pin 31. As illustrated in Fig. 1 of the drawings, the wobbler 29 is shown in a neutral position, the wobbler being adjustable angularly in both directions from the neutral position to provide for reversing the flow of fluid from the pump, as well as adjusting the output volume of the pump. The shaft 30 is rotatably mounted in the casing and in the cyl-

inder block in bearings 32 and 33, respectively, and projects outwardly through the end member 21 of the casing for connection to a suitable electric motor 34 or other prime mover.

A shaft 35 for the motor M is rotatably mounted in the casing and the cylinder block by means of bearings 36 and 37, respectively. This shaft carries a wobbler device 39 which is pivotally mounted on the shaft by means of a pin 40, so that the wobbler may be adjusted angularly on the shaft to vary the stroke of the motor pistons 41.

The inner surface 42 of the end member 21 is preferably flat and forms one wall of a valve chamber 43, in which the valves of both the pump and the motor operate. The cylinder block 24 is recessed as illustrated to provide an opposed flat surface 44 forming the opposite wall of the valve chamber. Operable in the lower portion of the valve chamber 43 and to control the flow of fluid to and from the pump cylinders 26 is a wheel-like valve 45 of the type more fully disclosed and claimed in U. S. Letters Patent No. 2,190,812, of Gunnar A. Wahlmark, dated February 20, 1940. This valve is mounted on an eccentric 46 on the shaft 30 and is operable to connect the pump cylinder ports 47 alternately to the peripheral portion 48 of the valve chamber or to an inner annular passage 49 in the valve. Operable in the upper portion of the valve chamber 43 is a wheel-like valve 50 for the motor. This valve is mounted on an eccentric pin 51 on the motor shaft 35 and is operable during rotation of the shaft to connect the motor piston ports 52 alternately to the peripheral portion 53 of the valve chamber or an inner annular passage 54 in the valve. As will be apparent from the drawing, the provision of a common valve chamber for the pump and valves provides a direct connection for the flow of fluid from the pump to the motor (or vice versa) through the narrow midportion of the valve chamber. A second passage for the flow of fluid between the pump and the motor is provided in the end member 21 at 55, this passage having an annular portion 56 in the lower part of the end member communicating with the inner passage 49 of the valve 45 and having an annular portion 57 in the upper part of the end member communicating with the inner passage 54 of the valve 50.

A pair of high pressure relief valves 60 and 61 are provided to limit the pressures in the passages between the pump and motor. These valves are normally held seated by means of coiled springs 64 and 65. The connection between these high pressure relief valves and the passages between the pump and the motor will be more fully described in connection with the description of the circuit.

Preferably, a rotary pump 70 is mounted on the casing 20 and driven from the right hand end of the pump shaft 30. The pump 70, as illustrated, is of the form shown in U. S. Letters Patent No. 2,132,813, of Gunnar A. Wahlmark, dated October 11, 1938, and serves to supply fluid at approximately 150 pounds per square inch pressure to the pump-motor circuit to maintain this circuit full at all times and for actuating control mechanisms. Cooperating with the pump 70 to maintain the pump-motor circuit full of fluid are a pair of check valves 71 and 72, the operation of which, as well as the flow of fluid from the pump 70, will be described in greater particularity hereinafter. Preferably, a relief valve 73 is backed by a spring 74 which may be

adjusted so that the valve 73 opens on pressures in excess of 150 pounds per square inch. This valve is connected in the output circuit of the pump 70 to limit the pressure of the makeup and control fluid.

In actuating a table or other support of a machine tool, it is desirable to obtain a plurality of relatively slow feed speeds and also a relatively high or rapid traverse speed. For convenience 10 "table" will hereinafter be employed to designate the part or element driven by the transmission. Also for convenience, operation of the transmission in one direction or the other will be designated in terms of forward or reverse movement of the table. It is to be understood, however, that any character of support or element, whether reciprocatory or rotary, and whether a part of a machine tool or some other mechanism, is intended. While the pump P and motor M combine to provide a large number of different speeds of the motor shaft 35, an additional means is provided for utilizing these motor shaft speeds for obtaining traverse movements of the table and for reducing these speeds still further to obtain feed movements. To that end, the transmission includes a planetary gearing, generally designated 15, operatively interposed between the motor shaft 35 and a driven shaft 76, journaled in a ball bearing 77, in alignment with the motor shaft. This gearing may take any one of a number of well known forms but preferably comprises a sun gear 78 formed on the end of the motor shaft 35, one or more planet gears 79 meshing with the sun gear 78 and rotatably supported on a radially outwardly projecting flange 80 formed on the inner end of the shaft 76. The planet gear 79 also meshes with a ring gear 81 which is slidable longitudinally in the casing 82 surrounding the planetary gearing. The gear 81 has an integral inwardly and thence longitudinally extending annular flange 83 carrying an annular piston 84 reciprocable in a cylinder 85. The ring gear has an outer beveled annular brake face 86 engageable with a corresponding beveled stationary brake ring 87 when the piston 84 is moved toward the right in Fig. 1. The ring gear 81 also carries an annular clutch member 88 provided with a beveled face 89 engageable with a corresponding beveled clutch face 90 on the flange 80 of the shaft 76, so that when the piston 84 is moved toward the left the clutch faces 89 and 90 are engaged and the planetary gearing elements are locked together to rotate as a unit. Under this condition, the driven shaft 76 will 50 rotate in unison with the motor shaft 35. With the ring gear held stationary against the brake ring 87, the driven shaft 76 will be operated at a speed lower than that of the motor shaft 35 due to the reduction caused by the planetary gearing which is then free to operate.

In Fig. 7, by way of illustration, there is disclosed one form of table, support or carriage that may be actuated by the transmission. Represented is a milling machine table 350 and suitable gearing for driving the same from the driven shaft 76. At its ends the table has depending end brackets 351 and 352 suitably bolted thereto. A feed screw 353 is rotatably mounted in these brackets and has squared ends 354 enabling it to be rotated manually for "set up" adjustments. The screw 353 passes through a pair of spaced stationary nuts 355 secured to the bed 356 of the machine.

A drive gear 357 is slidably keyed to the screw 75 and is rotatably mounted on the bed 356. The

drive from the transmission shaft 76 to the screw is completed by suitable gearing indicated by the numerals 358, 359, 360, 361 and 362. This gearing connecting the transmission shaft 76 to the table is shown by way of illustration herein and forms the subject matter of a copending application of Gustaf H. Ekstrom and Bengt R. Granberg, Serial No. 323,780, filed March 13, 1940, now Patent No. 2,371,045 issued March 6, 1945.

The control mechanism for the wobbler devices of the pump and motor will now be described. The pump wobbler device 29 is adjustable by means including a member 111 slidably in a keyway 112 extending longitudinally in the pump shaft 30. The member 111 has a radially extending portion 113 engaging in a radial opening in the wobbler device so that movement of the member 111 toward the left from the position shown in the drawing pivots the wobbler device in a clockwise direction to cause a flow of fluid from the pump to the motor, operating the motor in a forward (table) direction, whereas, movement of the member toward the right rotates the wobbler device in a counterclockwise direction, causing a reverse flow of fluid from the pump to the motor and a reversal of the motor and table movement. A tubular control member 115 for the pump is slidably mounted in a bore 116 in the cylinder block 24 and is connected with the member 111 by means of a ball bearing 117. The control member 115 has a radial bore therein, and into this bore extends one end of a lever 119 pivotally mounted intermediate its ends on a pin 120. The motor wobbler device 39 has a similar slidably control member 122 positioned in a keyway 123 in the motor shaft 35 and provided with an outwardly extending arm 124 which engages in a bore in the wobbler device. A tubular control member 126 is slidable in a bore 127 in the cylinder block 24 and is connected to the member 122 by means of a ball bearing 128. The tubular member 126 has a radially extending bore which receives one end of a lever 130 pivotally mounted intermediate its ends on a pin 131.

In the form illustrated herein, the pump control lever 119 and the motor control lever 130 are arranged to be operated by piston and cylinder devices, and, furthermore, are arranged to have their operative positions determined by additional piston and cylinder devices. Thus, the remaining end of the lever 119 extends into a diametrical bore in a piston 141 which is slidably mounted in a cylinder 142. The remaining end of the lever 130 extends into a diametrical bore in a piston 144 slidably mounted in a cylinder 145. Arranged immediately adjacent and parallel to the cylinder 142 is a cylinder 146 containing a piston 147, the pistons 141 and 147 having cut-away portions provided with rack teeth 148 and 149, respectively, which mesh with a pinion 150 fast on a shaft 151. Herein this shaft is extended outwardly of the casing to receive a manual control handle 151' shown in dashed lines in Figs. 1 and 2. This geared connection between the pistons 141 and 147 permits actuation of the lever 119 by the piston 147, as well as by the piston 141. For convenience the pistons 141 and 147 or the devices of which they form a part will be known as reversing or rack pistons or devices, while the piston 144 or the device will be known as the main neutralizing piston or device.

Parallel to but midway between the axes of the pistons 141 and 147 is a cylindrical bore 157 partially lined with a sleeve 156. A cylindrical

plunger 158 is slidably mounted in the sleeve 156 and at its left hand end projects into the paths of the right hand ends of the pistons 141 and 147. The plunger 158 is connected to the piston 144 by means of a lever 159 which is pivoted intermediate its ends on a pin 134. The upper end of the lever 159 enters a bore 160 in the piston 144, whereas, the lower end of the lever enters a bore 161 in the plunger 158. The piston 144 has a slightly smaller pressure area than either of the pistons 141 or 147, and herein is operated by fluid at 110 pounds per square inch pressure, whereas pistons 141 and 147 are operated by fluid at 150 pounds pressure, so that when the piston 144 and one of the pistons 141 or 147 are subjected to fluid pressure at the same time, the piston 141 or 147 will control. The connections just described are such that, by supplying fluid to the cylinder 142 through a port 162, the piston 141 will be moved toward the right and will cause a swinging movement of the pump control lever 119 in a counterclockwise direction, thus causing a movement of the tubular control member 115 toward the left and an adjustment of the wobbler device 29 in a clockwise direction about the pivot 31. If fluid is supplied to the cylinder 146 through a port 163, the rack and pinion connection will cause a movement of the piston 141 toward the left, thus causing an adjustment of the wobbler device 29 in a counterclockwise direction from that shown in the drawings. Regardless of whether the piston 141 moves to the right or the piston 147 moves to the right, the plunger 158 will be moved to the right and, through the intervening lever 159, piston 144, and lever 130, will cause an adjustment of the motor control member 126 toward the right from the position shown in the drawings, so as to reduce the stroke of the motor pistons as the stroke of the pump pistons is increased. Since the movement of the motor wobbler device 39 is always in the same direction from a neutral position, the direction of rotation of the motor shaft will be reversed when the fluid flow from the pump is reversed. The plunger 158 may for convenience be referred to as the auxiliary neutralizing plunger.

The extent to which the pump and motor wobbler devices are pivoted by action of the pistons 141 and 147 is at times determined by an additional piston and cylinder device mounted in an auxiliary casing 155 supported from the casing 20. To that end the casing 155 is formed with a bore 165 open at its left hand end, as viewed in Fig. 1, to the sleeve 156. Reciprocable in the bore is a hollow piston 166 formed with a recess 167 opening through the left hand end of the piston, as viewed in Fig. 1, and closed after assembly of the device by a plug 168. Suitably mounted in the casing 155 in threaded engagement therewith is a screw adjusting device 169 projecting through an aperture 170 in the piston 166 and formed at the end projecting into the recess of the piston with a head 171 larger than the aperture 170 so as to limit inward movement of the piston 166. At its outer end the screw device 169 carries a suitable cap nut 172 which may be manually or through mechanical means rotated to adjust the screw 169 to the desired longitudinal position. As described more fully hereinafter, fluid may be supplied to the right hand end of the bore 165 through a port 173 to maintain the piston 166 in its left hand or pressure actuated position as determined by adjustment of the screw device 169. The piston 166 thus is operable to limit the movement of the

plunger 158 toward the right and thereby operates to limit the movement of the pistons 141 and 147 and thus eventually determine the operative positions of the wobbler devices of the pump and motor. It is pointed out at this time that the pressure areas of the pistons 141 and 147 and of pistons 166 and 168 are so proportioned that for given pressures acting on the various pistons, the pistons 166 and 168 operating jointly overcome either piston 141 or 147, thereby making the piston 166 effective as a limit stop to movement of the pistons 141 or 147 to the right. The piston 166 and the device of which it forms a part will for convenience be hereinafter known and referred to as the feed control piston or device.

The various control piston and cylinder devices are intended primarily to be actuated or governed by fluid pressure, and they are herein shown to be controlled by means including a main valve means, generally designated 179, and composed of a valve 180 cylindrical in form and slidably mounted in a bore 181. This valve has five positions, a central neutral position and feed and traverse positions on each side of neutral; the feed and traverse positions to the left of the neutral position being arranged to effect movement of the table toward the right, and the positions to the right of neutral being arranged to effect movement of the table toward the left. The valve 180 has a longitudinally extending port 182 therein which communicates with annular recesses 183, 184, 185 and 186 in the periphery of the valve. The port 182 extends all the way to the right hand end of the valve so as to discharge into the valve bore which in turn discharges into a return line to the tank as hereinafter more fully described. The valve also has a longitudinally extending port 187 which communicates with annular recesses 188, 189 and 190 in the periphery of the valve. The valve bore 181 is provided with annular grooves 191, 192, 193, 194, 195 and 196, the function of which will become more readily apparent from the description of the circuit hereinafter.

In addition to the parts already described, the hydraulic system includes a pressure reducing valve means, designated 200, a pressure directing valve means 201, a shunting valve means 202, a changeover valve means 203, and a relieving valve means 204. The construction of these valves and their connection in the hydraulic system, as well as their function, will be described in connection with the description of the circuit portion of the hydraulic system.

In the lower portion of Figs. 1 and 2 there is illustrated a tank 205 containing a supply of fluid, such as oil. A suction line 206 which includes a strainer or filter 207 extends from the tank 205 to the intake 208 of the makeup pump 70. The output of the pump 70 is discharged through an outlet 209 and to a conduit 210 connected to the outlet and to the relief valve 73. Any fluid passing through the relief valve 73 returns to the tank 205 through a conduit 211. Valve 73 is preferably adjusted to maintain a makeup pump pressure of about 150 pounds per square inch, suitable for use as control fluid in governing certain piston and cylinder devices and certain valve means. To that end, there is connected to the conduit 210 a control fluid supply conduit 212 leading to the annular groove 193 of the main valve means 179.

Provision is made herein to utilize comparatively high control fluid pressures, so as to obtain quick and positive action of the hydraulically controlled devices and to provide the necessary holding force for those devices at the high speeds.

and heavy loads, while at the same time obtaining increased efficiency in the transmission by employing lower charging pressures. This is accomplished by the inclusion of the pressure reducing valve means 200. This valve means comprises a cylindrical valve 215 slidable in a bore 216. The valve is formed with a comparatively wide annular recess 217 and a narrow recess 218. The latter communicates through a small radial port 219 with a longitudinal passage 220 opening through the left hand end of the valve, as viewed in Figs. 1 and 6, to discharge to the bore 216. The valve is constantly urged to the right, as viewed in Figs. 1 and 6, by a compression spring 221 where it abuts a small lug 222 leaving an annular passage 223 to which the right end of the valve 215 is always exposed. The bore 216 is formed with two annular grooves 224 and 225 so spaced that they are bridged by the recess 217 when the valve 215 abuts the lug 222. The recess 218 in turn is so spaced relative to the recess 217 and the groove 225 as to permit communication thereof with the groove 225 when the valve 215 is shifted to the position shown in Fig. 6. The bore 216 is also formed with a constantly open port 226 connected to the tank through a conduit 227. A small bleed passage 228 leads from the groove 225 to the annular passage 223. The valve will thus function in well known manner to shift the valve 215 to the left and thereby restrict the groove 225 until the desired reduced pressure is established in this groove, herein about 110 pounds per square inch.

The valve means just described has its groove 224 connected by a conduit 230 to the control fluid supply conduit 212. Leading from the groove 225 is a charging fluid conduit 231 divided at its other end into branches 232 and 233 leading, respectively, to the check valves 71 and 72 for supplying makeup or charging fluid to the closed system of the transmission. As already described, high pressure relief valves 60 and 61 are connected to the passages connecting the ports of the main pump P and the motor M and constituting the closed transmission circuit. Such connection of the high pressure valves in the transmission circuit is effected through the medium of a conduit 235 communicating at one end with the peripheral portion 48 of the valve chamber 43, and at the other end with a port 236 controlled by the check valve 60. A conduit 237 communicates at one end with the annular portion 56 of the passage 55 and at the other end with a port 238 controlled by the check valve 61. Fluid flowing past the check valve 60 is returned to the conduit 237 by a conduit 239, while, conversely, fluid flowing past the check valve 61 is returned to the conduit 235 through a conduit 240.

Considering next the shunt forming valve means 202, this valve means is so constructed and is so connected in the system as to short circuit the ports of the main pump P and thus prevent any crawling of the table actuated by the transmission due to the eccentricity or slight departure from a truly neutral position of the wobbler 29 when the system is in neutral position. The valve means 202 comprises a cylindrical valve 243 reciprocable in a bore 244. Intermediate its ends the valve is formed with a very wide annular recesses 245 and at its upper end, as viewed in Figs. 1 and 5, is formed with a narrow recess 247. This latter recess communicates through radial ports 248 with a longitudinal passage 249 opening through the lower end of the valve so as to discharge to the bore 244 which is connected to

the tank through a conduit 250 open to the bore through the end thereof and thus in alignment with the passage 249. Valve bore 244 is formed with three annular grooves 251, 252 and 253. These grooves are so spaced axially of the bore that groove 251 registers with recess 247, while grooves 252 and 253 are bridged by the recess 245 when the valve is in the position shown in Figs. 1 and 5. When the valve is shifted upwardly to the position shown in Fig. 2, grooves 251 and 252 are bridged by the recess 245, while groove 253 is blocked. Independently of the valve 243, grooves 251 and 252 are constantly interconnected by a passage 255 having interposed therein a restricted orifice 256.

The groove 252 is by a conduit 257 connected to the conduit 235 and groove 253 is by a conduit 258 connected to the conduit 237. It will thus be seen that when the valve is in the position shown in Fig. 1, wherein grooves 252 and 253 are bridged, the ports of the main pump P have been connected together so as to form a shunt circuit about the motor M. Thus, should there be a slight discharge even though the wobbler 29 is intended to be in absolute neutral position, the fluid will merely flow through the pump and the valve means 202 and there will be no creeping of the table. It is to be noted that under this condition the main pump P is through the passage 255, the orifice 256, and the annular recess 247 and radial port 248 connected to the tank. This orifice is so proportioned that a pressure of approximately eighty pounds per square inch is required to force through it the oil pumped by the makeup pump 70. Thus, there is always maintained a makeup or charging pressure of approximately eighty pounds per square inch, which is lower than the control pressure maintained by the makeup pump relief valve 73, and thus reduces the work done by the pump 70 when the system is in neutral.

The orifice 256 and the passage 255 serve an additional function. When it is desired to move the table by hand, the prime mover driving the pumps P and 70 is stopped, while the valve means 202 is retained in the position shown in Figs. 1 and 5. Under those conditions, actuation of the transmission by hand forces the oil to the tank through the orifice 256 and the passage previously described, so that after one revolution of the transmission all the oil is discharged therefrom and movement of the table by hand is effected with little effort, because it is no longer necessary to force the oil through the transmission itself.

The valve means 202 may be controlled in any desired manner. Herein, however, it is for purposes of illustration disclosed as actuated electrically through the medium of a solenoid 259 under the control of a switch 260 appropriately connected in electrical circuit with the solenoid 259. The valve 243 is shifted to its upper position when the solenoid is energized and is returned by gravity or equivalent means to its lower position when the solenoid is deenergized. As already described, the valve is shown in its lower or deenergized position in Figs. 1 and 5, and is shown in its energized or upper position in Fig. 2.

Normally, the various devices determining the direction and rate of operation of the transmission and hence the direction and rate of movement of the table or support driven thereby are hydraulically actuated and governed under the control of the main valve means 179. To that end, groove 192 is by a conduit 265 connected to

port 162 of cylinder 142, while groove 194 is by conduit 266 connected to port 163 of cylinder 146. Groove 195 is by a conduit 267 connected to a port 268 discharging to one end of cylinder 85 constituting a part of the actuating means for the planetary gearing 75. A port 269 communicating with the opposite end of the cylinder 85 is by a conduit 270 connected to annular groove 196 of the valve means 179. The remaining annular groove 191 of the valve means 179 is by a conduit 271 and by a conduit 272 adapted at times to be connected to a port 273 opening to the bore 165 between the plunger 158 and the piston 166. Similarly, groove 196 of the valve means 179 is adapted at times to be connected with the port 173 opening to the bore 165 at the extreme right hand end thereof, as viewed in Figs. 1 and 2. This communication is effected by means including a conduit 274 communicating at one end with the conduit 270 and a conduit 275 communicating at one end with the port 173.

The main valve means 179 also controls the pressure directing valve means 201 simultaneously and coordinately with the reversing pistons 141 and 147. To that end, a conduit 276 branches from the conduit 265 and communicates with a port 277 opening through one end of a bore 278 in which is reciprocable a cylindrical valve 279. Branching from the conduit 266 is a conduit 280 connected to a port 281 opening through the opposite end of the bore 278. Intermediate its ends the bore 278 is formed with three equally spaced, annular grooves 282, 283 and 284. The outside grooves 282 and 284 are by conduits 285 and 286 connected, respectively, to the conduits 235 and 239, thus providing connection to opposite sides of the closed transmission circuit. The intermediate groove 283 has leading therefrom a conduit 287, and interposed in this conduit is a check valve means, generally designated 288. This means provides a valve seat 289 against which a check valve 290 is constantly urged by a compression spring 291. It will be appreciated from a consideration of Figs. 1 or 2 that the check valve is so disposed as to permit flow in a direction away from the groove 283, but to prevent flow in the opposite direction. Limited flow in this opposite direction is permitted by the provision of a small orifice 292 formed centrally of the check valve 290. Valve 279 has a single wide control recess 293.

Though already described, it is believed desirable to mention briefly at this point that, during operation of the system under the control of the main valve means 179, control fluid will be supplied to one or the other of the cylinders 142 and 146, thereby urging the associated piston to the right, as viewed in Fig. 1, and thus either directly, if the piston 141 is actuated, or through 55 the pinion 150, if the piston 147 is actuated, pivoting the lever 119 to tilt the wobbler 29 for forward or reverse operation of the pump. Such shift of the pistons 141 or 147 will in turn act to shift the plunger 158 and through lever 159, piston 144, and lever 130 tilt the wobbler 39 of the motor. It will be seen that the direction of the tilt of the wobbler for the pump is determined by which of the pistons 141 or 147 is actuated, but that the wobbler of the motor is tilted in but one direction. The extent of tilt of both wobblers is determined by the piston 166 and the adjustment of the screw device 169. If the right hand end of the bore 165 is connected to tank, the plunger 158 may, of course, be shifted the maximum distance to the right, resulting in maximum

displacement of the pump and minimum displacement of the motor, in other words, to a high rate of operation of the transmission. This is herein accompanied by such adjustment of the planetary gearing as will produce rapid traverse movement of the table or other support actuated by the transmission. Should control pressure be supplied to the right hand end of the bore 165, the piston 166 would be shifted to the left to the extent permitted by engagement thereof with the head 171 of the screw device 169. Movement of the plunger 158 to the right would thus be limited by its engagement with the piston 166, and thus results in operation of the transmission at a particular rate predetermined and fixed by adjustment of the screw device 169. As herein disclosed, control fluid is at the same time supplied to the actuating means for the planetary gearing so as to adjust the same to obtain a feed rate of operation of the transmission. Thus, though the rate of operation may be varied throughout the entire range of the transmission by adjustment of the screw device 169, once that adjustment has been determined, the system will, when operating under the control of the main valve 179, operate either at the rapid traverse rate of the transmission or at a particular preadjusted feed rate.

While control of the various piston and cylinder devices determining the rate and direction of drive of the transmission is normally hydraulical under the control of the main valve means 179, provision is herein made for manual control of the wobbler devices 29 and 39 by means including the handle 151, for obtaining any feed rate of movement within the range of the transmission. To that end, the changeover valve means 203 and the pressure relieving valve means 204 are provided. The changeover valve means comprises a cylindrical valve 300 slidable in a bore 301. The valve is provided with three comparatively wide, annular recesses 302, 303 and 304, all of approximately the same length. A fourth narrower recess 305 is provided intermediate the recesses 303 and 304. This latter recess communicates through radial ports 306 with a longitudinal passage 307 opening through the lower end of the valve, as viewed in Figs. 1 and 4, to discharge to the bore 301. The bore in turn is provided with six annular grooves 308, 309, 310, 311, 312 and 313, all of the same width as the recess 305 in the valve. Of these grooves, the first four are equally spaced near the upper end of the bore 301, while the latter two have the same spacing as the other four, but are separated from the first named four. The openings to the bore are completed by a port 314 opening through the end of the bore and connected by a conduit 315 to the tank. The recesses and the grooves are so positioned that in the upper position of the valve, that is, in the position shown in Figs. 1 and 4, grooves 309 and 310 will be bridged by the recess 303, groove 311 will register with recess 305 and thus be connected to tank, and groove 313 will be uncovered and thus also be connected to tank. In the lower position of the valve, that is, the position shown in Fig. 2, grooves 308 and 309 will be bridged by the recess 302, grooves 310 and 311 will be bridged by the recess 303, and grooves 312 and 313 will be bridged by the recess 304, thus leaving no groove in communication with the longitudinal passage 307 of the valve.

The valve may be actuated in any desired manner. It is for purposes of disclosure, however, herein shown as actuated electrically by a sole-

noid 316 under the control of a switch 317 suitably connected in electrical circuit with the solenoid. When the switch is closed and the solenoid energized, the valve is shifted to its upper position, as shown in Figs. 1 and 4. When the switch is open and the solenoid deenergized, the valve returns by gravity or equivalent means to the lower position, shown in Fig. 2.

The pressure relieving valve means 204 comprises a cylindrical valve 320 reciprocable in a bore 321. The valve is formed intermediate its ends with a wide, annular recess 322 and is formed on either side of the recess with narrow recesses 323 and 324 equally spaced from the intermediate, wide recesses. Extending longitudinally of the valve is a passage 325 opening through the right hand end of the valve, as viewed in Fig. 1, and communicating with this longitudinal passage through radial ports 326 and 327, respectively, are the recesses 323 and 324. The valve is constantly urged to the left, as viewed in Fig. 1, by a compression spring 328 where it strikes a boss 329 to leave an annular passage, the fluid within which may at all times act on the end of the valve.

The valve bore is provided with a port 330 opening through the end thereof to the annular passage formed about the boss 329. The bore is additionally formed with annular grooves 332 and 333, and with an enlargement 334 of the bore 321. Opening to this enlarged portion of the bore is a port 335 communicating through a conduit 336 with the tank 205. The various recesses, grooves and ports are so spaced that when the valve 320 is shifted to the left, as in Fig. 1, the groove 332 will be in communication with the recess 322, while groove 333 will register with the recess 324 and thus will be connected to the tank. When the valve is shifted to the right, to the position shown in Fig. 2, this position being determined by abutment of the valve with an elongated boss 337, grooves 332 and 333 will be bridged by the recess 322. In this circuit arrangement, recess 323 serves merely as a trap for leakage fluid.

These valve means control the supply or exhaust of control fluid from the bore 165 and also control the source of the charging fluid supplied to the cylinder 145. To that end, the changeover valve means is interposed between the conduits 274 and 275 leading to the port 173 with the conduit 274 connected to the groove 312 and the conduit 275 connected to the groove 313. Groove 308 is connected to the conduit 287 leading from the pressure directing valve means 201, while groove 309 is by a conduit 340 connected to the left hand end of the cylinder 145. It will be seen that the charging fluid supplied to the cylinder 145 from the pressure directing valve means 201 is taken directly from the closed transmission circuit during automatic control and thus will transmit to the piston 144 the surge pressure which appears during change from traverse to feed, or in a reversal in direction of operation by the transmission of the table or support driven thereby. The changeover valve means also makes possible the supply of a uniform charging pressure from the pressure reducing valve means 200 during manual control. To that end groove 310 of valve 203 is by a conduit 341 connected to the charging pressure conduit 231 leading from valve means 200. This same pressure is utilized to shift the valve 320 to the right and to that end groove 314 is connected to port 330 by a short conduit 342.

The valve means 204 is interposed between the

conduits 271 and 272 with the conduit 271 connected to the groove 333. The hydraulic system is completed by an enlarged passage 345 connected by a conduit 346 to tank. The bore 181 of the main valve means 179 as well as one end of the cylinders 142 and 146 open to this large passage 345.

Having described the hydraulic system, the operation thereof for certain typical and exemplary conditions will be described, in order that the invention may be better understood and the functions and operations of the various control means and valves better correlated. Let it be assumed, therefore, that the prime mover is driving the pumps and that the system is in neutral, that is, with the valve 180 of the main control valve means 179 in its intermediate or neutral position shown in Fig. 1. Let it also be assumed that all of the other valves are in the positions shown in Fig. 1, particularly that the valve means 202 is in its deenergized position. Under these conditions, charging fluid is supplied to the cylinder 145 from the pressure reducing valve means 200 through conduit 231, conduit 341, grooves 310 and 309 now bridged by recess 303 of valve 300, and conduit 340. Piston 144 will thus be shifted to the right and through lever 159 and plunger 158 return pistons 141 and 147 to their neutral position. As a consequence, the wobbler device 29 of the main pump P will be in neutral position, that is, at right angles to the shaft 30 so that no discharge of fluid will take place, while the wobbler device 39 of the motor M will be given its maximum tilt to give the motor M its maximum capacity. The shunt valve means 202 will connect the conduits 251 and 258 so that, should there be a slight displacement from the pump P, the fluid would merely circulate through the pump and not be supplied to the motor to cause a creeping of the transmission. Makeup fluid as well as control fluid will continue to be pumped by the makeup pump 70, and this will discharge to the transmission circuit and hence to the conduits 257 and 258. This makeup fluid is permitted to discharge to tank through the passage 255, orifice 256, groove 251, annular recess 247 and radial ports 248 to the longitudinal passage 249 of the valve 243. Control fluid is supplied to the longitudinal passage 187 of the main control valve through conduits 210 and 212, groove 193, recess 189, and the radial passage leading from the recess to the passage 187. From the passage 187 control fluid is supplied through recess 190, annular groove 196, and conduit 270 to the port 269 of cylinder 85 adjusting the planetary gearing to feed rate of operation of the transmission, and through conduit 274 which now, however, is blocked by valve 300. Control fluid is also supplied to the conduit 271 which now, however, is blocked by the valve 320.

To condition the system for operation either under hydraulic control or under direct manual control, switch 260 is closed to energize solenoid 259 and thus shift valve 243 upwardly to the position shown in Fig. 2. In this position the conduits 257 and 258 are no longer interconnected but are both blocked, thus rendering the transmission circuit ready for operation. If the system is to be controlled by the main valve means 179, the switch 317 is opened to deenergize the solenoid 316 and thus permit the valve 300 to move downwardly to the position shown in Fig. 2. As a result grooves 312 and 313 will now be bridged by the recess 304 and conduits 274 and 275 will thus be interconnected. At the same

time grooves 308 and 309 will be bridged by the recess 302 connecting the conduit 340 to the conduit 287 so as to supply the cylinder 145 with charging fluid from the transmission circuit as distinguished from charging fluid taken from the pressure reducing valve. Grooves 310 and 311 will now also be bridged by the recess 303 and fluid under pressure will thus be supplied to the left hand end of the bore 321 causing a shift of the valve 320 to its right position. Such a shift of the valve 320 will temporarily connect conduits 271 and 272 through a bridging of grooves 332 and 333 by recess 322.

The valve 180 may now be shifted to any one of its four positions to obtain feed or traverse rate of operation of the transmission in either a forward or a reverse direction. Initial shift of the valve 180 is manual with subsequent shifts to obtain a predetermined cycle of operation, either manually or by means of dogs on the support as is the conventional practice. Let it be assumed, for purposes of this disclosure, that the valve 180 is shifted one step to the left so as to take its feed right position shown in Fig. 2. As a result, control fluid is now supplied from the longitudinal passage 187 of the main valve through recess 189 to groove 192 and thence through conduit 265 to the cylinder 142. This will shift piston 141 to the right and thus through the lever 119 tilt the wobbler device 29 of the pump. Such shift of the piston 141 to the right also shifts plunger 158 to the right, and thus through the lever 159 shifts piston 144 to the left which in turn, through the lever 130 and associated mechanism, reduces somewhat the tilt of the wobbler device 39 of the motor M. At the same time, cylinder 146 is connected to tank through conduit 266, groove 194, recess 185, longitudinal passage 182, passage 345, and conduit 346. Port 273, opening to the bore 165 intermediate the plunger 158 and the piston 156, also is now connected to tank through conduit 272, grooves 333 and 332 now bridged by recess 322, conduit 271, groove 191, recess 184, longitudinal passage 182 and thence to tank, as already described. Also connected to tank is port 268 of cylinder 85, permitting shift of the piston 83 in a direction to condition the planetary gearing for feed rate of operation. This connection to tank is through the conduit 267, groove 195, recess 185 and thence through passage 182 to tank. Control fluid is supplied to the port 269 of the planetary gearing control means through recess 190 and conduit 270 to effect the shift just mentioned as made possible by the exhaust of fluid from the other end of the cylinder. Pressure fluid is also supplied from the conduit 270 through the conduit 274 and the conduit 275, which are now interconnected by a bridging of the grooves 312 and 313 by the recess 304 of the changeover valve to port 173. Inasmuch as port 273 is now connected to tank through conduit 272, groove 333, recess 322, groove 332, conduit 271, groove 191 and recess 184 to the longitudinal passage 182 in the valve 180, the fluid supplied to the right hand end of the piston 146 will cause the same to be shifted to the position shown in Fig. 2 and thus to determine the position of the plunger 158, which in turn determines the positions of the wobbler devices and hence the rate of operation of the transmission. Control fluid is also supplied from the conduit 265 through conduit 276 to port 277, while the opposite end of the bore 278 is through conduits 280 and 266, groove 194, and recess 185 connected to the longitudinal passage 182

and thus to tank. The valve 279 will thus be shifted to its left position, as viewed in Fig. 2, appropriately connecting conduit 287 to the low pressure or makeup side of the transmission circuit. As already described, this will subject the piston 144 to the temporarily increased surge pressure in the transmission circuit, occurring in a change from traverse to feed or during reversal, so as to assure that the plunger 158 will follow the movements of the plungers 141 or 147.

Should now the valve 180 be shifted manually or by dogs another step to the left to its traverse right position, the system would operate at a traverse rate of speed. This position of the main valve means 179 is shown in Fig. 3 and, from a consideration of that figure, it will be seen that control fluid is continued to be supplied to the cylinder 142 and to the right hand end of the bore 278 of the pressure directing valve means 201 through the same connections just described. Control fluid is now, however, supplied to the port 268 and exhausted from the port 269, so as to permit shift of the piston 84 in a direction adjusting the planetary gearing 75 for rapid traverse operation. To that end, conduit 267 is through groove 195 and recess 190 connected to the control fluid passage 187 of the main valve, while conduit 270 is now through recess 186 connected to the longitudinal passage 182 and thus to tank. With conduit 270 connected to tank as just described, the right hand end of bore 165 also will be connected to tank, thus permitting piston 166 to move to its extreme right position under the influence of the piston 141. There will thus be given to the pump wobbler device 29 the maximum angular position, while the motor wobbler device 39 will be given the minimum angular position so as to obtain the maximum rate of operation of the transmission itself. It is believed apparent that the operation of the system to the other feed or traverse position will be the same except, of course, that the transmission and the support will be driven in the opposite direction.

Should it be desired to place the system under the direct manual control of an operator instead of under the control of the main valve means 179, this may be done by returning the valve 180 to its neutral position, shown in Fig. 1, and by energizing the solenoid 316 so as to shift the valve 300 to its upper position, as shown in Fig. 1. Such positioning of the valve 180 in neutral will first of all connect both cylinders 142 and 146 to tank. These connections, respectively, include conduit 265, groove 192, recess 184, and longitudinal passage 182, and conduit 266, groove 194, recess 185, and longitudinal passage 182. Likewise, both ends of the bore 278 of the pressure directing valve means 201 are connected to tank, this being effected through conduits 276 and 280 connected, respectively, to conduits 265 and 266. Shift of the valve 300 first of all connects the left hand end of bore 321 of the valve means 204 to tank through conduit 342, groove 311, radial ports 305, and longitudinal passage 307, permitting the spring 328 to return the valve to its left position, as shown in Fig. 1. This shift of the valve 320 breaks the connection between conduits 271 and 272 and connects conduit 272 to tank through recess 324, radial port 327, longitudinal passage 325, port 335 and conduit 336. The shift of the valve 300 has already broken the connection between conduits 274 and 275 and has connected conduit 275 to tank through groove 313, which now is open directly to the port 314. Thus, with

pressure relieved from the bore 165, both between the plunger 158 and the piston 166, and behind the piston 166 as well as in the cylinders 142 and 146, the operator may now manually adjust the transmission for operation in either direction and at any desired rate within the feed range by rotating the shaft 151 as by means of handle 151'. This shift of the valve 300 to the position shown in Figs. 1 and 4 also re-established connection between the conduits 340 and 341 through bridging of grooves 309 and 310 by recess 303. The cylinder 145 is now connected to the pressure reducing valve means 200, and the increased pressure resulting as the piston 144 is shifted to the left will act on the right hand end of the valve 215 through the bleed passage 228, and will shift the same to the left until recess 218 registers with groove 225 (see Fig. 6). The excess fluid may then flow to tank through radial port 219 and longitudinal passage 220. Thus it will be seen that the feed control device is rendered inoperative and the wobbler devices 29 and 39 may be adjusted for operation at any desired feed rate within the range of the transmission by manual operation of the handle 151', since this handle is mechanically connected to the wobblers by the intervening connecting parts 151, 150, 141, 119 and 115, and 158, 159, 144, 130 and 126.

Finally, should it be desired not merely to control the system directly but to actually move the support manually, the solenoid 259 is deenergized to permit the valve means 202 to return to position shown in Fig. 1 wherein the intake and discharge ports of the main pump P are short circuited and wherein groove 251 now is in registry with recess 247 to be connected with tank through radial ports 248 and longitudinal passage 249. The prime mover also is preferably stopped. As the support is moved, the transmission is, of course, actuated and will force the fluid in the transmission circuit through the orifice 256 and thus discharge to tank. After one complete revolution of the motor M and pump P, all of the fluid in the transmission circuit will have been exhausted, thus obviating the necessity of constantly forcing the fluid through the transmission and thereby making the movement of the support very easy.

It is believed that the foregoing description and recapitulation of the operation, taken in connection with the drawings, will render the invention completely and readily understandable. It is also believed that we have perfected unique and improved means for providing direct manual control of the direction and rate of operation of the transmission, while also providing for automatic or hydraulic control through a main valve means. When the system is arranged for automatic operation at a feed speed determined by the feed control piston 166 and its adjusting screw 169, it may be changed over to manual operation and controlled by handle 151', after which, when it is changed back to automatic operation the original feed speed is again obtained since there has been no change in the adjustment of screw 169. Under manual control the rate of feed is proportional to the distance the handle 151' is moved away from its neutral position of Fig. 1.

Other features and advantages are also believed apparent, particularly the provision for discharge of fluid from the transmission circuit when it is desired to move the support by hand, as well as the provision in a pressure reducing valve of means for permitting escape of a portion of the

fluid to enable fluid to be relieved from the cylinder 145.

We claim as our invention:

1. In a system for motivating a support, motivating means for driving the support, means controlling the motivating means to drive the support at predetermined rates within the range of the motivating means, power operated means for actuating said control means to obtain said predetermined rates, and manual means alternatively operable to actuate said control means to obtain movement of the support at any rate throughout the range without limitation to the predetermined rates.

2. In a system for motivating a support, motivating means for driving the support, said means being adjustable to operate throughout a range of rates, power operated means controlling the motivating means to operate at a predetermined rate within the range, and alternatively operable manual means for actuating said control means to obtain operation at any rate within the range without limitation to the set rates and without disturbing the setting of the power operated means for subsequent return thereby to said set rates.

3. In a hydraulic system, a transmission adjustable to operate over a range of feed rates, control means for the transmission causing the transmission to operate at a predetermined feed rate, power operated means for actuating said control means, and manually operable means optionally effective on said control means for obtaining operation of the transmission at any desired feed rate within the range, said manually operable means including a handle shiftable from a neutral position to different feed rate positions with the rate of feed determined by the extent of shift and the direction of feed by the direction of shift of the handle from neutral.

4. In a system for motivating a support, motivating means for driving the support, said means being adjustable to operate throughout a range of rates, control means governing adjustment of said motivating means, pilot means governing said control means to cause operation of said motivating means at set rates, manually operable means directly actuating said control means to obtain operation at any rate within the range without limitation to the set rates, and means for rendering the pilot means ineffective when the manually operable means directly actuate the control means.

5. In a system for motivating a support, motivating means for driving the support, said means being adjustable to operate throughout a range of rates, means for effecting adjustment of said motivating means, manual means associated with said adjustment effecting means for direct actuation thereof, presetable means operable when supplied with an actuating medium to limit adjustment of said motivating means to a set rate, and means exercising control over said adjustment effecting means and said presetable means to cause operation of the motivating means at set rates or to free said adjustment effecting means and said presetable means for direct manual actuation of said adjustment effecting means to obtain any desired rate within the range of rates.

6. In a system for motivating a support, motivating means for driving the support, said means being adjustable to operate throughout a range of rates, manual and motivating medium actu-

ated means for effecting adjustment of said motivating means, presetable means operable when supplied with an actuating medium to limit adjustment of said motivating means to a set rate, and means exercising control over said adjustment effecting means and said presetable means to cause operation of the motivating means at set rate or to free said adjustment effecting means and said presetable means for direct manual actuation of said adjustment effecting means to obtain any desired rate within the range of rates.

7. In a system for motivating a support, motivating means for driving the support, said means being adjustable to operate throughout a range of rates, shiftable means for effecting adjustment of said motivating means with the extent of movement of said shiftable means determining the rate of operation of the motivating means, hydraulically actuated presetable means operable when supplied with fluid under pressure to constitute a stop limiting the shift of said shiftable means to the preset rate, manual means associated with said shiftable means for direct actuation thereof, and means controlling the supply or exhaust of fluid to said presetable means to effect operation of the motivating means at the preset rate or to permit direct manual operation of said shiftable means to any desired position without limitation by the presetable means.

8. In a system for motivating a support, motivating means for driving the support, said means being adjustable to operate throughout a range of rates and in forward or reverse direction, hydraulically operated means causing operation of the motivating means in either direction and at set rates, manual means associated with said hydraulically operated means for manual actuation thereof, and means relieving the hydraulic pressure in the hydraulically operated means to permit direct manual adjustment for operation of the motivating means in either direction and at any rate within the range of the motivating means.

9. In a system for motivating a support, motivating means for driving the support, said means being adjustable to operate throughout a range of rates and in either forward or reverse direction, a piston and cylinder device shiftable in either direction from a neutral position to determine the direction of operation of the motivating means and determining the rate of operation of the motivating means by the extent of shift from neutral position, manual means associated with said piston and cylinder device for direct manual shifting thereof, a hydraulically actuated device forming when actuated a limit stop for said piston and cylinder device determining the extent of shift of said piston and cylinder device and including an adjustable means for determining the actuated position of the hydraulically actuated device, and a hydraulic control circuit for said piston and cylinder device and said hydraulically actuated device including a main control valve exercising control to obtain operation of the motivating means at set rates, and changeover valve means rendering said hydraulically actuated device inoperative to permit manual shift of the piston and cylinder device in either direction and to any desired extent.

10. In a hydraulic system, a transmission operable at different rates and in forward and reverse directions and a control system for governing the operation of the transmission comprising

a piston and cylinder device shiftable in opposite directions from a neutral position to determine the direction of operation of the transmission and determining the rate of operation of the transmission by the extent of shift from neutral position, a second piston and cylinder device including adjustable means for limiting the movement of the piston of said second device, said piston when actuated by the supply of fluid pressure to the device acting as a limit stop controlling the extent of shift of said first piston and cylinder device, manually operable means associated with said first piston and cylinder device for direct manual operation thereof, a main control valve means, means for supplying control fluid thereto, a circuit connection from said main valve means to said first mentioned piston and cylinder device, a circuit connection from said main valve means to said second piston and cylinder device, and a valve means interposed in the last mentioned circuit connection and operable to place said second piston and cylinder device under the control of said main valve means or to disconnect the same therefrom and relieve the second piston and cylinder device of all fluid pressure.

11. In a hydraulic system, a transmission operable at different rates and in forward and reverse directions and a control system for governing the operation of the transmission comprising a piston and cylinder device shiftable in opposite directions from a neutral position to determine the direction of operation of the transmission and determining the rate of operation of the transmission by the extent of shift from neutral position, a second piston and cylinder device including adjustable means for limiting the movement of the piston of said second device, said piston when actuated by the supply of fluid pressure to the device acting as a limit stop controlling the extent of shift of said first piston and cylinder device, manually operable means associated with said first piston and cylinder device for direct manual operation thereof, a main control valve means, means for supplying control fluid thereto, a circuit connection from said main valve means to said first mentioned piston and cylinder device, and means alternatively operable to place the second piston and cylinder device under the control of said main valve means to obtain operation of the transmission at set rates or to remove said second piston and cylinder device from the control of said main valve means and connect the same to tank to permit manual operation of said first mentioned piston and cylinder means to any extent desired.

12. In a hydraulic system, a transmission operable at different rates and in forward and reverse directions, and a control system for governing the operation of the transmission comprising a first piston and cylinder device with the piston shiftable in opposite directions from a neutral position to determine the direction of operation of the transmission and determining the rate of operation of the transmission by the extent of shift from neutral position, a cylinder forming means, a plunger reciprocable in one end of the cylinder so formed and abutted by said piston and cylinder device, a piston reciprocable in the other end of the cylinder so formed, adjustable means limiting the movement of said piston toward said plunger, said piston through said plunger acting as a stop limiting the shift of said first piston and cylinder device, manually operable means associated with said first piston and cylinder device for direct manual operation thereof, a main con-

5 trol valve means, means for supplying control fluid to said valve means, a circuit connection from said valve means to said first mentioned piston and cylinder device, a circuit connection from said main valve means to said cylinder between said plunger and said piston, and a valve means interposed in the last mentioned circuit connection and operable to complete the connection from the main valve means to the cylinder or to disrupt the connection and relieve the space between the piston and plunger of all fluid pressure.

13. In a hydraulic system, a transmission operable at different rates and in forward and reverse directions, and a control system for governing the operation of the transmission comprising a first piston and cylinder device with the piston shiftable in opposite directions from a neutral position to determine the direction of operation of the transmission and determining the rate of operation of the transmission by the extent of shift from neutral position, a cylinder forming means, a plunger reciprocable in one end of the cylinder so formed and abutted by said piston and cylinder device, a piston reciprocable in the other end of the cylinder so formed, adjustable means limiting the movement of said piston toward said plunger, said piston through said plunger acting as a stop limiting the shift of said first piston and cylinder device, manually operable means associated with said first piston and cylinder device for direct manual operation thereof, a main control valve means, means for supplying control fluid to said valve means, a circuit connection from said valve means to said first mentioned piston and cylinder device, a circuit connection from said main valve means to said cylinder between said plunger and said piston, a valve means interposed in the last mentioned circuit connection and operable to complete the connection from the main valve means to the cylinder or to disrupt the connection and relieve the space between the piston and plunger of all fluid pressure, and valve means controlling the supply of fluid to the end of said cylinder containing the piston also controlling said last mentioned valve means.

14. In a hydraulic system, a transmission operable at different rates and in forward and reverse directions, and a control system for governing the operation of the transmission comprising a pair of piston and cylinder devices, rack teeth on the pistons, a pinion meshing with the rack teeth to interconnect the pistons, an operating lever rigid with the pinion for manually shifting the pistons, means including a plunger common to both pistons connected with the transmission to cause the transmission to operate in one direction or the other dependent upon the direction of shift of the pistons and to operate at a rate determined by the extent of shift of the pistons, a third piston and cylinder device including an adjustable screw determining shift of the piston of the last mentioned device in a direction toward said plunger to form a limit stop for shift of the plunger by either of said pair of piston and cylinder devices, and a hydraulic control circuit including said piston and cylinder devices, a main valve having a neutral position relieving both of the pair of piston and cylinder devices of fluid pressure and a position on either side of neutral directing fluid under pressure to one or the other of said pair of piston and cylinder devices, said valve in all three positions directing fluid under pressure to said third piston and cylinder device, and auxiliary valve means operable in one

position to permit a supply of fluid under pressure from said main valve means to said third piston and cylinder device and operable in another position to interrupt the supply of pressure fluid and to relieve said third piston and cylinder device of all fluid under pressure to permit ready manual operation of said pair of piston and cylinder devices when said main valve means is in neutral.

15. In a system for motivating a support, a motivating means operable at different rates and in forward and reverse directions, and a control means for the motivating means comprising a shiftable member having a neutral position, means interconnecting said member with the motivating means to determine the direction of operation thereof by the direction of shift of the member from neutral position and the rate of operation by the extent of shift from neutral position, hydraulically actuatable means for shifting said member, a manual means associated with said member for optional manual shift thereof, a main control valve means governing shift of said member hydraulically, means adjustable to limit the extent of movement of said shiftable member hydraulically, and means operable selectively to render said last mentioned means effective to limit the shift of said shiftable member when the latter is under the control of said main valve means or to render said limit means ineffective and permit any desired shift of said shiftable member by said manual means without disturbing the adjustment of said limit means.

16. In a hydraulic system, a transmission operable at different rates and in forward and reverse directions, and a control system for governing the operation of the transmission comprising a first and a second piston and cylinder device, means interconnecting said devices, manual means rigid with said interconnecting means for direct manual actuation of said piston and cylinder devices, means including a third piston and cylinder device acting in opposition to said first and second devices associating said first and second devices with said transmission causing the direction of shift of the devices to determine the direction of operation of the transmission and the extent of shift of said first and second devices to determine the rate of operation of the transmission, a fourth piston and cylinder device operable when supplied with fluid under pressure to provide an adjustable stop limiting the extent of movement of said first and second devices, and a control circuit including said piston and cylinder devices and also including a source of control fluid for said first, second and fourth devices, a main valve means governing the supply of control fluid to said last named devices, a pair of sources of actuating fluid for said third piston and cylinder device, and valve means alternatively connecting said third piston and cylinder device with one or the other of said pair of sources and alternatively connecting said fourth piston and cylinder device to said main valve means or to tank.

17. In a hydraulic system, a hydraulic transmission operable at different rates and in forward and reverse directions and having a closed working circuit, and a control system for governing the operation of the transmission comprising a first and a second piston and cylinder device, means interconnecting said devices, manual means rigid with said interconnecting means for direct manual actuation of said piston and

cylinder devices, means including a third piston and cylinder device acting in opposition to said first and second devices associating said first and second devices with said transmission causing the direction of shift of the devices to determine the direction of operation of the transmission and the extent of shift of said first and second devices to determine the rate of operation of the transmission, a fourth piston and cylinder device operable when supplied with fluid under pressure to provide an adjustable stop limiting the extent of movement of said first and second devices, and a control circuit including said piston and cylinder devices and also including a source of control fluid for said first, second and fourth devices, a main valve means governing the supply of control fluid to said last named devices, pressure directing valve means governed by said main valve means operable to provide a connection to the low pressure side of the working circuit of the transmission, pressure reducing valve means connected directly to the source of control fluid for said first and second piston and cylinder devices, and a valve means operable in a first position to place said fourth piston and cylinder device under the control of said main valve means and in that position to connect said third piston and cylinder device to said pressure reducing valve means, and operable in a second position to remove said fourth piston and cylinder device from the control of said main valve means and in that position to connect said third piston and cylinder device to said pressure reducing valve means.

18. In a hydraulic system, a hydraulic transmission operable at different rates and in forward and reverse directions and having a closed working circuit, and a control system for governing the operation of the transmission comprising a first and a second piston and cylinder device, means interconnecting said devices, manual means rigid with said interconnecting means for direct manual actuation of said piston and cylinder devices, means including a third piston and cylinder device acting in opposition to said first and second devices associating said first and second devices with said transmission causing the direction of shift of the devices to determine the direction of operation of the transmission and the extent of shift of said first and second devices to determine the rate of operation of the transmission, a fourth piston and cylinder device operable when supplied with fluid under pressure to provide an adjustable stop limiting the extent of movement of said first and second devices, and a control circuit including said piston and cylinder devices and also including a source of control fluid for said first, second and fourth devices, a main valve means governing the supply of control fluid to said last named devices, pressure directing valve means governed by said main valve means operable to provide a connection to the low pressure side of the working circuit of the transmission, pressure reducing valve means connected directly to the source of control fluid for said first and second piston and cylinder devices, and a valve means operable in a first position to place said fourth piston and cylinder device under the control of said main valve means and in that position to connect said third piston and cylinder device to said pressure directing valve means, and operable in a second position to remove said fourth piston and cylinder device from the control of said main valve means and relieve said fourth piston and cylinder device from the control of said main valve means.

der device of all fluid pressure to permit manual shift of said first piston and cylinder devices in either direction and to any desired extent, said last-mentioned valve means in its second position being operable to connect said third piston and cylinder device to said pressure reducing valve means, said pressure reducing valve means

including a passage permitting discharge to tank of the fluid discharged from said third piston and cylinder device as an incident to manual shift of said first and second piston and cylinder devices.
